G. MERLE, SR

VARIABLE CONDENSER

Filed Feb. 5, 1926

INVENTOR
George Merle Sr
BY
Howard E. Thompson
ATTORNEY

UNITED STATES PATENT OFFICE.

GEORGE MERLE, SR., OF BROOKLYN, NEW YORK.

VARIABLE CONDENSER.

Application filed February 5, 1926. Serial No. 86,318.

This invention relates to variable condensers and particularly to devices of this class employing two or more condenser units mounted in a single frame or support, each 5 condenser unit comprising rotor and stator plates; and the object of the invention is to provide a device of the class specified, constructed in such manner that two or more condenser units of a radio receiving circuit 10 may be contained in a single casing in which the separate condensers are operable; a further object being to provide means for independently rotating the rotors of the separate condenser units and with additional 15 means whereby rotors of all of the units may be collectively operated; a further object of my invention resides in the provision of a device of the class specified, so constructed that the rotors of the separate condenser 20 units may be adjusted relatively to the rotors of other condenser units for the purpose of tuning the upper coils or that part of the circuit in connection with which the condensers are employed, whereby when a proper relation 25 of the rotors of the separate units has been ascertained, the means for simultaneously operating all of the rotors may be moved into operative position, thereby producing a one knob control for all of the condenser units; and with these and other objects in view, the invention consists in a device of the class and for the purpose specified, which is simple in construction, efficient 30 in use, and which is constructed as herein- 35 after described and claimed.

The invention is fully disclosed in the following specification, of which the accompanying drawing forms a part, in which the separate parts of my improvement are designated by suitable reference characters in 40 each of the views, and in which:—

Fig. 1 is a face view of a part of a panel or other support showing my improved condenser mounted in connection therewith, 45 with parts of the construction broken away and in section; and,

Fig. 2 is a transverse section through the condenser shown in Fig. 1.

The condenser shown and described herein 50 is an improvement on that shown and described in a prior application for Letters Patent of the United States, filed by me April 10, 1925, and bearing Serial No. 22,104, and the distinctive features of my improved

structure are shown in the accompanying 5 drawing and hereinafter described.

In the drawing, I have shown for the purpose of illustrating one use of my invention, two frame members 5 and 6 which may be composed of rubber, bakelite or any similar 60 material. These frame members are secured together and spaced apart by corner posts 7 through which bolts or similar devices 8 may pass in securing the condenser to the panel or other support 9 of a radio receiving 65 apparatus. The frame members 5 and 6 are rectangular in form, and in the construction shown are divided by plates 10 and 11 extending from corner to corner, and crossing centrally into four triangular sections, in 70 which the separate condenser units are mounted. The plates 10 and 11 may be composed of insulating or conducting material, as may be desired, and are spaced from the stator plates 12, 13, 14 and 15 of the separate 75 condenser units, the stator plates 12 constituting one unit, the plates 13 another unit, etc.

The plates 12—15 in the construction shown are triangular in form and secured 80 within and between the frames 5 and 6 by bolts 16 passing through the corner portions of said plates as clearly seen in Fig. 1 of the drawing. One of the bolts of each condenser unit is extended to form terminals 17, with 85 which circuit wires may be connected. A plurality of rotor plates 12^a, 13^a, 14^a and 15^a are mounted for cooperation with the stator plates 12—15 of the separate units, and said 90 rotor plates are each mounted on shafts 18 which project forwardly through the frame 5 and through the panel 9, and are provided at their outer ends with knob dials 19, by means of which the shafts 18 and the rotor plates thereon may be rotated into and out of 95 engagement with the stator plates of the separate condenser units.

Mounted on each shaft 18 preferably between the frame 5 and the panel 9 are gears 20 which do not mesh with each other but 100 are adapted to mesh with a gear 21 mounted on a shaft 22 which is rotatably and slidably mounted in a bushing 23 mounted in the panel 9. The outer end of the shaft 22 is provided with a knob dial 24, by means of which the 105 shaft 22 and gear 21 may be rotated. The shaft 22 is provided with two annular grooves 25 and 26 in connection with which a spring-

pressed ball or other member 27 is adapted to operate to retain the gear 21 in engagement with the gears 20 as seen in Fig. 2 of the drawing, and when said ball is operating in the 5 groove 25, or to retain the gear 21 out of engagement with the gears 20 when the knob dial shaft and gear 21 have been moved outwardly by hand, and the ball 21 is in engagement with the groove 26 in said shaft 22. In 10 the last named position of the gear 21, it will be apparent that the separate rotor plates 12^a—15^a may be independently adjusted with respect to the stator plates 12—15, but by moving the gear 21 into the position shown 15 in Fig. 2 of the drawings, or into mesh with the gears 20, all of the rotor plates 12^a—15^a may be rotated through the single knob dial 24.

It will be understood that all of the rotor 20 plates may be coupled together in one circuit or by means of one conductor, or wires of separate circuits may be directed to the stator plates of the separate condenser units in the same manner as the coupling of the separate 25 circuit wires with the stationary plates of said units.

It will also be apparent that I am not necessarily limited to the specific shape or form of the stator or rotor plates nor the specific 30 movement imparted to said rotor or movable plates, nor am I necessarily limited to the other specific structural details herein shown and various changes therein and modifications thereof may be made within the scope of 35 the appended claims, without departing from the spirit of my invention or sacrificing its advantages.

With my improved construction, it will be noted that the mounting of the stator plates, 40 which are triangular in form in the construction shown, is such that the short sides of said triangular plates are arranged adjacent each other in the respective units so as to bring the intersection of said sides to the approximate 45 central portion of the frame, and the long sides of said plates are arranged in substantial parallelism and adjacent to the outer side edges of the front and rear plates of the frame, thus forming within the frame in a 50 compact fashion, a plurality of fields, each field containing the stator plates of separate and independent condenser units and the fulcrum or shafts of the rotor plates of the separate units are arranged centrally of and adjacent the long sides of the stator plates and the corresponding outer side edges of the frame plates. Thus, when all of the rotor 55 plates are moved within the fields of the stator plates, the entire unit is bounded by the edges 60 of the frame plates thereof. In other words, in the operation of the rotor plates, they are moved into said fields and outwardly with respect thereto and to the frame. With this construction, a very compact condenser unit 65 is produced, and a unit occupying the least

amount of space for packing, shipment and other purposes.

Having fully described my invention, what I claim as new and desire to secure by Letters Patent, is:—

1. A condenser of the class described comprising a frame, a plurality of independent condenser units in said frame and mounted in an edge to edge relation, each of said units comprising stator plates and rotor plates, 70 means for adjusting the position of the rotor plates with reference to the stator plates of the separate units, and means cooperating with the first named means of the separate units for actuating the rotor plates of all of the units from a single control.

2. A condenser of the class described comprising a frame, a plurality of condenser units in said frame, each of said units comprising stator plates and rotor plates, means for adjusting the position of the rotor plates with reference to the stator plates of the separate units, means cooperating with the first named means of the separate units for actuating the rotor plates of all of the units from a single control, said last named means being movable into operative and inoperative positions, and means for retaining the same in such positions, and said condenser units being mounted within the frame with the stator plates thereof edge to edge, and partition walls between the adjacent edges of said stator plates.

3. A condenser of the class described comprising a plurality of independent condenser units for controlling independent circuits, and means whereby the separate condenser units may be actuated for balancing adjustment, means involving a single control for operating collectively and simultaneously, 100 the rotor plates of all of the condenser units, said last named means involving gears on the shafts of the rotor plates, and another gear adapted to be moved into and out of mesh with the first named gears.

4. A condenser of the class described comprising a plurality of independent condenser units for controlling independent circuits, and means whereby the separate condenser units may be actuated for balancing adjustment, means involving a single control for operating collectively and simultaneously, 105 the rotor plates of all of the condenser units, said last named means involving gears on the shafts of the rotor plates, and another gear adapted to be moved into and out of mesh with the first named gears, and means for holding the last named gear in operative and inoperative positions.

5. A condenser of the class described comprising a plurality of independent condenser units for controlling independent circuits, and means whereby the separate condenser units may be actuated for balancing adjustment, means involving a single control for 125 130

- operating collectively and simultaneously, the rotor plates of all of the condenser units, said last named means involving gears on the shafts of the rotor plates, and another gear 5 adapted to be moved into and out of mesh with the first named gears, means for holding the last named gear in operative and inoperative positions, and means for subdividing the separate condenser units in said 10 frame.
6. A condenser of the class described comprising a rectangular frame composed of separate frame parts within and between which is supported a plurality of sets of stator plates, each set being independent of the other, and a plurality of sets of rotor plates mounted in the frame and cooperating with the separate sets of stator plates to form independent condenser units in said frame, 15 means involving knob dials on each unit for actuating the rotor plates thereof, and means involving another knob dial whereby the rotor plates of all of the condenser units may be controlled and operated from a single 20 control.
7. A condenser of the class described comprising a frame, a plurality of condenser units in said frame and each consisting of stator plates and movable plates, and the stator plates of said units being positioned edge to edge and adjacent in said frame, and means for operating the movable plates of each of said units.
8. A condenser of the class described comprising a frame, a plurality of condenser units in said frame and each consisting of stator plates and movable plates, the stator plates of said units being positioned edge to edge and adjacent in said frame, and independent control and operating devices for the movable plates of the separate units whereby each condenser unit may be operated independently of the other.
9. A condenser of the class described comprising a frame, a plurality of condenser units in said frame and each consisting of stator plates and movable plates, the stator plates of said units being positioned edge to edge and adjacent in said frame, independent control and operating devices for the movable plates of the separate units whereby each condenser unit may be operated independently of the other, and means involving a single control whereby all of the movable plates may be collectively operated.
10. A condenser of the class described comprising a frame, a plurality of condenser units in said frame and each consisting of stator plates and movable plates, the stator plates of said units being positioned edge to edge and adjacent in said frame, independent control and operating devices for the movable plates of the separate units whereby each condenser unit may be operated independently of the other, means involving a single control whereby all of the movable plates may be collectively operated, and means in the frame for subdividing the condenser units one from the other.
11. A condenser of the class described comprising a rectangular frame composed of spaced frame parts, a plurality of independent condenser units mounted within and between said frame parts, the inner ends of the stator plates of said units being adjacent centrally of said frame parts, the shafts of the rotor plates being spaced from and arranged adjacent the outer edges of the stator plates in each unit and at the side edges of said frame parts whereby said plates may be rotated inwardly into and between the frame parts and the stator plates therein and outwardly of said frame parts in the operation thereof.
12. A condenser of the class described comprising a rectangular frame composed of spaced frame parts, a plurality of independent condenser units mounted within and between said frame parts, the inner ends of the stator plates of said units being adjacent centrally of said frame parts, the shafts of the rotor plates being spaced from and arranged adjacent the outer edges of the stator plates in each unit and at the side edges of said frame parts whereby said plates may be rotated inwardly into and between the frame parts and the stator plates therein and outwardly of said frame parts in the operation thereof, and the stator plates of each unit having independent supporting means in said frame parts.
13. A condenser of the class described comprising a rectangular frame composed of spaced frame parts, a plurality of independent condenser units mounted within and between said frame parts, the inner ends of the stator plates of said units being adjacent centrally of said frame parts, the shafts of the rotor plates being spaced from and arranged adjacent the outer edges of the stator plates in each unit and at the side edges of said frame parts whereby said plates may be rotated inwardly into and between the frame parts and the stator plates therein and outwardly of said frame parts in the operation thereof, the stator plates of each unit having independent supporting means in said frame parts, means whereby the rotor plates of each unit may be independently operated, and means involving a single control in operative connection with the rotor plates of all of said units for simultaneously actuating the same.
14. A condenser of the class described comprising two spaced frame parts, a plurality of independent stator plate units mounted between said frame parts, edge to edge and in adjacent and spaced relation, forming a plurality of independent fields, a plurality of independent movable plate units cooperating with the stator plate units and mounted to

move into the fields of the separate stator plate units, and outwardly beyond said frame parts and stator plate units, in the operation thereof.

5 15. A condenser of the class described comprising two spaced frame parts, a plurality of independent stator plate units mounted between said frame parts, edge to edge, and in adjacent and spaced relation, forming a plurality of independent fields, a plurality of independent movable plate units cooperating

with the stator plate units and mounted to move into the fields of the separate stator plate units and outwardly beyond said frame parts and stator plate units, in the operation thereof, and means between said frame parts for partitioning the separate fields one from the other.

15 In testimony that I claim the foregoing as my invention I have signed my name this 1st day of February, 1926.

20 GEORGE MERLE, Sr.
